UNITED STATES PATENT OFFICE.

ARTHUR BIBERFELD, OF BERLIN, GERMANY, ASSIGNOR, BY MESNE ASSIGNMENTS, TO THE FIRM HEINRICH WOLLHEIM AND OSSENBACH, INDUSTRIESELSCHAFT M. B. H., OF BERLIN, GERMANY.

FACING FOR WALLS AND CEILINGS.

1,212,005.

Specification of Letters Patent.

Patented Jan. 9, 1917.

Application filed May 31, 1913. Serial No. 771,069.

To all whom it may concern:

Be it known that I, ARTHUR BIBERFELD, a citizen of the German Empire, and residing at Berlin, Germany, have invented certain new and useful Improvements in Facings for Walls and Ceilings, of which the following is a specification.

My invention relates to facings for walls and ceilings, and a primary object is to provide an improved facing comprising rods flexibly connected together, mounted loosely in a row on bands and so shaped that the structure thus formed can be bent transversely of its plane in both directions, the rods being attached to strips fastened on the wall.

It is well known to employ wooden rods flexibly connected laterally one with another for the facing of walls, but these known rods are mounted along their entire length on a continuous fabric and can be bent only in one direction transversely of the plane of the structure comprising the rods. As compared with these known facings the subject-matter of my invention has considerable advantages, namely, the possibility of adapting the facing in both directions conveniently to all curves, and by pushing the rods closer together or farther apart of covering lengths of wall which vary within certain limits with the same number of rods; the gaps which remain between the rods and which are covered from the outside owing to the suitable shape of the rods enable the wall to be suitably ventilated in a simple manner.

Several illustrative embodiments of my invention are represented by way of example in the accompanying drawing, wherein:—

Figure 1 is a front elevation showing one form of my improved wall facing, Fig. 2 is a horizontal section, enlarged, through the same, and Fig. 3 is a vertical section through the facing mounted on a wall; Figs. 4 and 5 are sections showing other forms of my improved facing.

Referring to the drawing, my facing is made as follows: The rods or bars α arranged in a row on the bands α' are attached by nails or screws at suitable distances apart on at least two battens or laths c and d fixed to the

wall, the lower edge of the rods bearing on a bottom batten or lath connected with the batten d . The facing is ended off above by a suitable strip i having an ornamental molding k . Each of these bars α is provided in one edge with a longitudinally extending groove α^2 which is substantially V-shaped in cross section with the side members or edges α^3 and α^4 curved outwardly, the edge α^4 being higher than the edge α^3 as is shown clearly in Fig. 2. The other edge of each bar α has a tongue α^5 extending longitudinally thereof and which is designed to enter the groove α^2 of the adjacent bar, said tongue being wider than the depth of the groove and the side walls thereof being concave, the side wall α^6 being longer than the side wall α^7 , so that the paneling formed by these connected bars may be flexed to a greater extent on one side than on the other, and the curved walls of the V-shaped grooves also facilitate the engagement of the tongues of the adjacent bars therewith. By so forming these bars, it will be understood that the paneling produced by connecting them, may be flexed or bent in either direction.

When walls having a wave-like surface are to be made with my improved facing, as shown in Figs. 4 and 5 the battens attached to the wall are formed as bow members f and g , to which the rods α are nailed as described above. By employing such bow members many kinds of ornamental effects can be obtained, quite apart from excellent insulation of heat of the room provided with such a facing being obtained by means of the corrugated facing which cannot be made out of slabs or panels of wood. In like manner curved ceiling facings can be made by means of bow members.

I claim:—

A flexible wall facing comprising transversely spaced flexible bands and a plurality of rods or bars mounted loosely on said bands, the said bars having a groove in one edge thereof, substantially V-shaped in cross section, and with the edges of the walls of said groove curved outwardly, the other edge of said rod having a tongue extending longitudinally thereof and adapted to pro-

ject into the groove of the adjacent bar, said tongue being wider than the depth of the groove and having inwardly curved or concave side walls to provide for the flexing of the bars laterally in relation to each other on one side or the other.

Copies of this patent may be obtained for five cents each, by addressing the "Commissioner of Patents, Washington, D. C."

In testimony whereof, I affix my signature in the presence of two witnesses.

ARTHUR BIBERFIELD.
